[57] CLAIM

The ornamental design for a bandage dispenser, as shown and described.

DESCRIPTION

FIG. 1 is an environmental perspective view of a bandage dispenser showing my new design;
FIG. 2 is a front elevational view thereof;
FIG. 3 is a top plan view thereof;
FIG. 4 is a left side elevational view thereof;
FIG. 5 is a rear plan view with the left side being a mirror image thereof;
FIG. 6 is an environmental right side elevational view thereof; and,
FIG. 7 is an environmental rear elevational view thereof.
The broken line showing of the cat in FIG. 6 and the bear in FIG. 7 is for illustrative purposes only, merely disclosing two of the various animals which can be used, and forms no part of the claimed design. The broken line showing of the bandage in FIG. 1 is for illustrative purposes only and forms no part of the claimed design.
